UNITED STATES PATENT OFFICE.

FRANK E. JONES, OF KIRKWOOD, ILLINOIS.

DESIGN FOR A PAPER BOX.

SPECIFICATION forming part of Design No. 28,041, dated December 14, 1897.

Application filed October 16, 1897. Serial No. 655,481. Term of patent 3½ years.

To all whom it may concern:

Be it known that I, FRANK E. JONES, a citizen of the United States, residing at Kirkwood, in the county of Warren and State of Illinois, have invented and produced a new and original Design for a Paper Box, of which the following is a specification, reference being had to the accompanying drawings, forming part thereof.

10 In the drawings, Figure 1 is a front view of a paper box, showing my new design. Fig. 2 is a rear view of the box. Fig. 3 is an end view thereof.

15 The leading feature of my design consists in a paper box shaped and ornamented to represent a chair.

The letter A designates the upper side, B the front side, C the rear side, and D and E the two ends, of the box. The rear side C 20 is extended upwardly to form the back F of the chair, and upon its front and rear sides said extended back F is ornamented with

lines to represent the uprights a, cross-pieces b, and intermediate rods c of a chair-back. The front side B is ornamented with lines to 25 represent the seat d, front legs f, and cross-braces e of a chair. Each of the ends D and E is ornamented with lines to represent the seat d, one front leg f and one rear leg g, and cross-braces h of a chair. The rear side C, 30 below the extension F, is ornamented with lines to represent the seat d, rear legs g, (shown as continuations of the uprights a,) and cross-braces k of a chair.

I claim—

35 The design for a paper box substantially as herein shown and described.

In testimony whereof I affix my signature in presence of two witnesses.

FRANK E. JONES.
